WARMING BAG OR THE LIKE

William A. Atkinson, Greggton, Tex.

Application March 7, 1952, Serial No. 18,824

Term of patent 14 years

(Cl. D92—2)

To all whom it may concern:

Be it known that I, William A. Atkinson, a citizen of the United States of America, residing at Greggton, in the county of Gregg and State of Texas, have invented a new, original, and ornamental Design for a Warming Bag or the like, of which the following is a specification, reference being had to the accompanying drawing, forming a part thereof.

The figure on the drawing is a front perspective view of a warming bag, showing my new design.

The back and the bottom of the warming bag are substantially plain.

I claim:

The ornamental design for a warming bag or the like, substantially as shown and described.

WILLIAM A. ATKINSON.
